UNITED STATES PATENT OFFICE

92,788

DESIGN FOR A FLOOR LAMP

George A. Wheeler, Wilmington, N. C.

Application April 20, 1934, Serial No. 51,474

Term of patent 7 years

To all whom it may concern:

Be it known that I, GEORGE A. WHEELER, a citizen of the United States, and a resident of Wilmington, in the county of New Hanover and State of North Carolina, have invented a new, original, and ornamental Design for a Floor Lamp, of which the following is a specification, reference being had to the accompanying drawing, forming part thereof.

The figure is a perspective view of a floor lamp, showing my new design.

I claim:—

The ornamental design for a floor lamp as shown.

GEORGE A. WHEELER.
